UNITED STATES PATENT OFFICE.

FRED REBELL, OF NORTH FREMANTLE, AUSTRALIA.

CONCRETE REINFORCING BOND AND CONNECTER.

Application filed June 30, 1925, Serial No 40,584, and in Australia September 22, 1924.

Heretofore it has been customary to weld or tie the reenforcing means of concrete slabs together and to cement concrete or other plastic slabs at their interconnections, 5 and it is this construction that the present inventions aims to avoid and yet at the same time to construct a concrete wall of plastic material not only insuring greater strength in the concrete or cement but also insuring 10 considerable strength in the bond or reenforcement, especially where the slabs are fabricated.

Another purpose is to provide, in a concrete building slab, an improved bond for 15 the slab itself as well as a secure bond between the slabs, the slabs to be conveniently cast in shallow molds or frames flat on the ground or floor or one over another, there being suitable lugs fixed to the frame at 20 regular intervals to form gaps in the edges of the slabs to hold the bonds or reenforcing rods in position. This method is equally applicable to concrete beams, columns, pipes, etc., and particularly for use in the construction of buildings, silos, bridges, etc. 25

Still another purpose is to provide an improved and secure interlocking between the bonding of the slabs, where two are edge-wise adjacent and where a third slab is positioned at right angles to the edge-wise adjacent slabs, the third slab overlying the joint between the first two slabs, it being possible that when the slabs are so connected, the gaps or notches in the slabs may 35 be closed by cement or other plastic material.

It is to be understood that the particulars herein given are in no way limitative and that, while still keeping within the scope of the invention, any desired modifications of 40 detail and desired proportions may be made in the apparatus according to the circumstances.

The invention comprises further features and combinations of parts to be hereinafter 45 set forth, shown in the drawings and claimed.

In the drawings:

Figure 1 is a view in elevation of portions of two edge-wise adjacent slabs, the 50 edges thereof being slightly spaced apart.

Figure 2 is a sectional view through edge-wise adjacent slabs, showing the bonding of the two slabs connected, curved bolts being employed for this purpose.

Figure 3 is a sectional view through two 55 edge-wise adjacent slabs and a third slab

at right angles to the first two slabs, with its edge overlying the joint or adjacent edges of the first two slabs, and also showing the connecting means between the several 60 slabs.

Figure 4 shows views of the character of bolts that may be used.

Figure 5 is a sectional view similar to Figure 4 but showing placed in position blocks 65 or strips acting to hold the loose concrete or mortar during the filling operation.

Figure 6 is a detail perspective view partly broken away showing a form of mold for making the slab constituting the invention. 70

Referring to the drawings, 1 and 2 designate a pair of concrete or cement slabs which may be placed edgewise adjacent each other, as shown in Figure 2 and as disclosed in Figure 3, or in any other position. The 75 slabs may be built up in order to break joints. Furthermore, the edges of the slabs are toothed, serrated or otherwise roughened, as indicated at 3, so as to insure holding the slabs in position until they are bonded 80 together.

In constructing concrete or cement slabs of this character, it is the purpose to use shallow molds or frames in position flat on the ground or floor or one over another. 85 While the molds or frames are designed to be shallow, it is obvious that they may be any depth or any size or shape. However, at regular intervals, affixed to the inner faces of the sides of the molds or frames are suitable lugs 4 which form gaps or notches 5 in the marginal edges of the concrete slab when the same is complete and set.

These lugs 4 are hollowed out, as shown at 6, for the reception of the looped ends 95 7 of the bonding rods are reinforcements 8. In other words, when molding a concrete or cement slab, as disclosed, the longitudinal and transverse bonding rods 8 are placed in position, said bondings being interwoven 100 with their loops 7 resting in the hollowed out portions 6 of the lugs 4. The concrete, cement or other plastic material is then poured into the mold, thereby filling up 105 around the bondings, and due to the provision of the lugs 4, the slabs will have, when completely molded and set, gaps or notches 5. The loops 7 of the bondings have their extremities flush with these serrated or toothed edges of the slabs, so as not to interfere with the edges of the slabs when the slabs are placed in position.

As shown in Figures 1 and 2, it is the purpose to connect or bond the loops 7 of the bondings together and in the present case it is the aim to use curved bolts 9, such as shown in Figures 2 and 3. It is obvious that the bolts may be made in any shapes so as to hold and secure concrete or cement or other plastic slabs together and in various positions. However, where the slabs are held edgewise adjacent each other, as in Figure 2, the bolts 9 are curved semicircular, that is, the shanks of the bolts, so as to accommodate the shanks to the position of the loops of the bondings. As shown, the head of the bolt bears against one loop while a nut 10 is threaded on the other end of the bolt to not only hold the bolt in place but also to connect the bonds.

The toothed or serrated edges of the slabs prevent movement or displacement of the slabs, particularly until the slabs are connected or united. After uniting the slabs in this way, it is possible to fill up the gaps or notches 5 and the spaces between the serrated edges with concrete, cement or other plastic material in order to insure a solid wall.

As disclosed in Figure 3, a third slab is positioned with one of its edges adjacent the faces of two edgewise adjacent slabs, the third slab 11 also being provided with the bonding designated by the same character as in the other figures, and to hold this third slab in position, an additional bolt 12 is provided. The shank of this bolt has a slight curve at a point in close proximity to the head of the bolt, so that the greater portion of the shank may assume a position, as in Figure 3, whereby the nut 13 may bear upon the loop of one of the bondings and in turn upon the head of a bolt 9. This not only holds the bolt 9 in position until its nut or other fastening means 10 is screwed on but insures a rigid union between the several slabs.

As previously stated, the notches or gaps 5 can receive a filler of concrete or cement to insure a solid union between the slabs of one wall and the slabs of a wall at right angles thereto. It is obvious that the bolts may be bent in any shape to suit the purpose, that is, the positions of the walls.

A further reason for serrating or roughening the edges of the slabs is to mainly increase bonding and cementing between the slabs and to allow the penetration of the cementing medium or grout (which is rather thick but semi-fluid in consistency) without the necessity of the interposition of a separating medium.

The reason for the reenforcement loops not protruding beyond the edge of the slab is to prevent the former from displacement or bending in handling or transporting of the slabs, also to allow the tensioning of the

reenforcement (by tightening the nuts) in the joints without the necessity of a separating medium between the slabs.

Where three slabs are joined in a common joint, the bolts mentioned alternate from right to left (heads versus nuts) every succeeding notch or gap, the stability of the connection being such that simple slabs with as little as three notches can be connected perfectly rigid (by bolts) even without cementing them together. This mode of connection also allows the tensioning of the reenforcement in the joint (by tightening the nuts), thus obviating or minimizing the tendency of crack formation along joints, possibly caused by contraction and expansion of the slabs and vibration and laxity of bond connections which may lead to corrosion and failure of the bonds in the crack.

While in Figure 5 the construction is similar to that in Figure 4, the bolts 9 and 12 are reversed to those in Figure 4 and in addition rods 14 are disposed at angles to and crossing each other as shown. The rods 14 pass on angles through the triple joint and through a wood piece or strip 15. This strip overlies the adjacent serrated edges of the slabs 1 and 2 to prevent the loss of the cement or grout. The rods 14 also pass through wood strips 16 which are triangular in cross section and are disposed in the corners adjacent where the slab 11 connects with the slabs 1 and 2, also acting to prevent the loss of the cement or grout. Suitable wedges 17 connect with the ends of the rods 14 which are slotted to receive the wedges, thereby retaining them in position and holding the loops 18 of the rods against the wood strip 15. The strips 15 and 16 serve as temporary mold walls at the joint to retain the grout or concrete or cement when being poured to fill the joint.

The invention having been set forth, what is claimed is:

1. In a building construction, a plurality of building slabs, certain of which are edgewise united, others of which having their edge portions overlying the united edge portions of the first slabs, the edgewise united slabs having notches or openings, bondings embedded in the slab and having loops located in the notches, means connecting the loops, the slab with its edge overlying said united edges having bondings, means connecting the last bondings with certain of the loops of the first bondings, wood fillers in the corners adjacent the slab which overlies the edgewise united slabs, and means passing through the joint of the several slabs and through the fillers for bonding the structure together.

2. In a building construction, a plurality of building slabs, certain of which are edgewise united and provided with bondings embedded therein, others of the slabs having

bondings and overlying the united edges of the first slabs, means for connecting the bondings of all the slabs, fillers in the corners between the edgewise united slabs and 5 the slab overlying the joint between the edgewise united slabs, a wood cover strip overlying the joint of the edgewise united slabs, and means passing through the cover strip and the joint between the several slabs 10 and through the fillers to insure rigidity.

3. In combination with the block elements of a masonry construction, a mechanical

bond consisting of reenforcing rods embedded in said elements and provided with loop terminals, and bent bolts spanning and 15 engaging the loops of the rods of adjacent elements, and nuts attached to the bolts at one extremity and bearing upon the loops for tensioning the rods when the nuts are tightened. 20

In testimony whereof he affixes his signature.

FRED REBELL.
